UNITED STATES PATENT OFFICE.

JOSEPH M. GREEN, OF MILL CREEK, UTAH.

PUMP.

SPECIFICATION forming part of Letters Patent No. 650,896, dated June 5, 1900.

Application filed April 26, 1899. Serial No. 714,570. (No model.)

To all whom it may concern:

Be it known that I, JOSEPH M. GREEN, a citizen of the United States, residing at Mill Creek, in the county of Salt Lake and State of Utah, have invented certain new and useful Improvements in Pumps, of which the following is a specification, reference being had therein to the accompanying drawings.

This invention has relation to improvements in pumps; and it consists in the novel construction and combination of parts of which it is composed, all as will be hereinafter fully explained, and particularly pointed out in the appended claim.

15 The annexed drawings, to which reference is made, fully illustrate my invention, in which—

Figure 1 represents a face view, partly in section, of my device. Fig. 2 is a plan view, 20 having the frame, pitmen, pistons, and eccentrics removed. Fig. 3 is a vertical transverse sectional view, and Figs. 4 and 5 are sectional views of the eccentric.

Referring by letter to the accompanying 25 drawings, A designates the pump, comprising a series of cylinders a, that are cast integral, having a plate b, an upper plate B, a top plate e, and a bottom plate f', provided with cups g', perforated at their lower end 30 and provided with valves c, pistons secured to the lower end of each piston-rod a', and an offset q', having channels leading to a reservoirs', provided with valves, all of which constitute the pump proper.

35 B designates the upper plate of the pump, and e is the top or cap plate, having the stuffing-boxes f for the piston-rods a', and said top plate is secured in position upon the cylinders by the rods k', passing through lugs 40 on the plate B and through perforations in the top plate and lower plates b and f' and secured by nuts l', thus firmly securing the cylinders between said upper and lower plates.

Above the cylinders is mounted a frame C, 45 consisting of the end castings h h, which are bolted to the top plate through their flanges i i and the end flanges j j of said plate. This frame comprises the end castings aforesaid and two parallel horizontal bars k k, that are 50 bolted at their ends l l to the top flange m of each end casting.

Above the frame and the cylinders is mount-

ed a horizontal shaft n, on which is keyed four eccentrics o, the same having grooves p, which receive a feather q on the inner face 55 of the upper and lower pitmen-heads s, and said heads are connected to one another by the vertical rods t, having the nuts u. To the heads aforesaid the upper end of each pitman is pivoted, as at v, while the lower ends 60 thereof are pivoted at w to a short arm x, comprising a wedge-shaped portion y, which passes through a corresponding opening z in the piston-rods a', and the same is secured in position upon said rods by a nut b' upon the 65 screw ends c' of the portion y, while the opposite end is provided with a screw end d', upon which a nut e' is secured, whereby the lower end of each pitman is pivoted. The pistons are constructed with vertical openings m', above which is a valve n', that plays 70 loosely upon the piston-rods, and a packing o' is interposed between the upper and lower plates comprising the piston. Each of these cylinders communicate with a reservoir by a 75 passage p' in an offset q', forming a part of said cylinders, and in the top of this offset are vertical openings r', providing a passage from said cylinders to a chamber or reservoir s', that provides for the flow of liquids from 80 the cylinders. The outlet-passages entering this reservoir are each provided with an independent valve t', which operates only with the piston - chamber connected therewith through this passage. This reservoir has its 85 outlet at the top, and the vertical movement of the piston-rods which lift the liquid forces the latter through the channels into the receiving-chamber and out the opening or outlet. The upper portion of each piston-rod 90 passes through a guide-opening u' in the cross-bars v', which are bolted at w' to the parallel bars of the frame.

In operation the shaft n is set in motion, 95 thus carrying with it the eccentrics, which operate the piston-rods, the pistons drawing the water through the lower plates into the cylinders, where it is lifted and forced through the passages into the reservoir and through the outlet, and a pump as herein described 100 is durable and readily taken apart for storing or shipping and at the same time cheap to manufacture.

Having thus described my invention, what

I claim, and desire to secure by Letters Patent, is—

The within-described pump, comprising the series of cylinders, having the offset and formed of a single piece, the lower plate provided with the perforated cups and valves *c*, plates *b*, *B*, top plate *e*, the pistons, having the perforations and formed of two parts, having the packing, and the valve *n'*; the reservoir mounted upon the offset and communicating with the cylinders by the channels *p'*, and the valves *t'*, arranged above said chan-

nels and within the reservoir; the piston-rods, having the openings *z*, the wedge-shaped blocks or arms *y*, the pitmen and frame, composed of the end standards, side bars and cross-bars *v'*, and the eccentrics, mounted on the shaft *n*, all as shown and described. 15

In testimony whereof I have affixed my signature in presence of two witnesses.

JOSEPH M. GREEN.

Witnesses:

GEORGE STANLEY,
LUCAS P. COWLEY.
